UNITED STATES PATENT OFFICE.

CYNTHIA WACASER, OF KANSAS CITY, MISSOURI.

DESIGN FOR A WASHBOILER.

47,310.

Specification for Design.

Patented May 4, 1915.

Application filed July 24, 1914. Serial No. 852,912. Term of patent 14 years.

To all whom it may concern:

Be it known that I, CYNTHIA WACASER, a citizen of the United States, residing at Kansas City, county of Jackson, and State of Missouri, have invented a new, original, and ornamental Design for Washboilers, of which the following is a specification, reference being had to the accompanying drawing, forming part thereof.

The figure is a perspective view of a wash boiler, showing my new design.

I claim:

The ornamental design for a wash boiler, as shown.

In witness whereof I have affixed my signature in the presence of two witnesses.

CYNTHIA WACASER.

Witnesses:

H. C. RODGERS,
G. Y. THORPE.
